STERILIZER

John A. Salvia, Rochester, N. Y., assignor to Wilmot
Castle Company, Rochester, N. Y., a corporation of
New York

Application November 2, 1956, Serial No. 43,646

Term of patent 14 years

(Cl. D83—1)

FIG. 3

FIG. 4

F.G.S.

Fig. 1 is an elevational view of the right side of a sterilizer, showing my new design;

Fig. 2 is an elevational view of the left side thereof;

Fig. 3 is an elevational view of the rear thereof;

Fig. 4 is an elevational view of the front thereof, with the door in normal closed position; and

Fig. 5 is an elevational view of the front thereof, with the door in open position.

I claim:

The ornamental design for a sterilizer, substantially as shown.
